UNITED STATES PATENT OFFICE

153,500

DESIGN FOR A TOY GUN

Paul D. Chapin, Hayward, Calif.

Application August 4, 1947, Serial No. 140,697

Term of patent 14 years

(Cl. D34—15)

To all whom it may concern:

Be it known that I, Paul D. Chapin, a citizen of the United States of America, residing at the city of Hayward, county of Alameda, and State of California, have invented a new, original, and ornamental Design for Toy Gun, of which the following is a specification, reference being had to the accompanying drawings, forming part thereof.

Figure 1 is a perspective view on a reduced scale of the toy gun showing my new design.

Figure 2 is a side elevational view thereof.

Figure 3 is a top plan view thereof.

I claim:

The ornamental design for a toy gun, as shown.

PAUL D. CHAPIN.
